V. L. DE DONTNEY,
ROBE RAIL LOCK FOR AUTOMOBILES,
APPLICATION FILED DEO. 13, 1911.

1,029,493.

Patented June 11, 1912.

UNITED STATES PATENT OFFICE.

VERKIE LUCAS DE DONTNEY, OF DENVER, COLORADO.

ROBE-RAIL LOCK FOR AUTOMOBILES.

1,029,493.

Specification of Letters Patent. Patented June 11, 1912.

Application filed December 13, 1911. Serial No. 665,591.

To all whom it may concern:

Be it known that I, VERKIE LUCAS DE DONTNEY, a citizen of the United States, residing in the city and county of Denver 5 and State of Colorado, have invented certain new and useful Improvements in Robe-Rail Locks for Automobiles; and I do declare the following to be a full, clear, and exact description of the invention, such as 10 will enable others skilled in the art to which it appertains to make and use the same, reference being had to the accompanying drawings, and to the characters of reference marked thereon, which form a part of this 15 specification.

My invention relates to improvements in means applied to the robe rails of automobiles and other vehicles to prevent the removal or theft of robes or other articles 20 left in the machine. While a device of this character may be employed in many relations, it is particularly advantageous in connection with automobiles for the reason that it becomes necessary to leave these machines in the street for long periods of time, 25 while their owners are absent. It is, therefore, important that provision be made for securing robes and other articles, as wearing apparel, in such a manner that they can 30 not easily be removed by evilly disposed persons. This is the object of my improvement, and it consists of equipping the robe rail with arms extending upwardly therefrom at each extremity and forming thereon 35 a series of vertically-arranged ratchet teeth adapted to interlock with spring-actuated rods carried by a vertically movable hollow bar, the extremities of the said bar being arranged to straddle the upright arms of 40 the robe rail, while the rods which interlock with the ratchet teeth enter grooves in the bottom of which teeth are formed. Provision is also made for disconnecting the said rods from the ratchet teeth of the robe rail 45 arms by the insertion of a key in a key hole formed in the center of said bar. Any suitable means may be employed for unlocking the device, no attempt having been made in the drawing to illustrate more than a conventional arrangement which is operative 50 for the purpose.

The lock, of course, may be made as complicated and as difficult to unlock without the use of the regular key, as may be desired, or as circumstances may seem to require.

Having briefly outlined my improved construction, I will proceed to describe the same in detail, reference being made to the accompanying drawing, in which is illustrated an embodiment thereof.

In this drawing: Figure 1 is a cross section, taken through the body of an automobile or other similar vehicle, just in front of the robe rail, which is equipped with my improved locking device. Fig. 2 is a detail view of the robe rail and my improved locking attachment, the parts being shown on a larger scale and partly broken away for lack of room on the sheet. Fig. 3 is a fragmentary top plan view of the device, looking in the direction of arrow 3, Fig. 2, parts being shown in section. Fig. 4 is a cross section, taken on the line 4-4 of Fig. 2, looking toward the right. Fig. 5 is a top plan view in detail, illustrating the overlapping inner extremities with the key in place and adjusted to disengage the rod extremities from the ratchet teeth, the key being shown in horizontal section.

The same reference characters indicate the same parts in all the views.

Let the numeral 5 designate the robe rail, which, as illustrated in the drawing, is secured to the back of the front seat of the vehicle by the use of brackets 6 having upper and lower arms 8 and 9, perforated to receive fastening screws 10. Each of these brackets is also equipped with an upright arm 12, the two arms 12 being located at the opposite extremities of the robe rail proper. Each arm 12 is vertically grooved on its inner surface, as shown at 13, ratchet teeth 14 being located at the bottoms of the grooves, the latter being of sufficient depth 95 to form guides for the outer extremities 15 of the ratchet rods 17, the outer ends of the said rods being beveled to coöperate with the ratchet teeth of the arms 12, the construction of the said teeth and their interlocking rod extremities being such that, as the bar 18, within which the rods 17 are located, is moved downwardly, the rod extremities slip past the ratchet teeth and automatically interlock with said teeth when the downward movement of the bar ceases, each rod being normally thrust outwardly to its limit of movement by a coiled spring 19, acting on a stop 20 with which each rod is equipped, the opposite extremity of the spring engaging the stationary stop 21, extending across the hollow bar 18 on the in-

side, the said stop 21 being perforated to allow the rod to slide freely therein. The stop 21 thus forms a guide for the rod, as well as a stop for the spring. Each rod is further guided by passing through a perforation 22, formed in the closed end 23 of the bar, the latter being equipped with flanges 24 at its opposite extremities, which straddle the upright arms 12, thus guiding the bar in its vertical movement up or down in the performance of its function in connection with the upright arms.

The body portion 25 of the bar 18 is semi-circular in shape in cross section, its free edges being bent upwardly into the cavity of the said body portion, which is hollow for the purpose. These inwardly bent parts 26 have their outer surfaces roughened, preferably, whereby they are adapted to take a firm hold of the robe or other article which is to be held thereby. This body portion of the bar co-operates with the robe rail 5 to perform the securing function, the rail being allowed to enter or partially enter the hollow body member 25 of the bar, as the latter is forced downwardly into engagement with the robe or other article hanging upon the said rail.

The portion 27 of the bar in which the rods 17 are located extends above the semi-circular body part 25, being centrally secured to the latter and extending longitudinally thereto. The inner extremities of the rods 17 are flattened, as shown at 28, and overlap each other, the overlapping parts being slotted, as shown at 29. The top of the semi-circular part 25, midway of the center thereof, is reinforced, as shown at 30, this reinforcement being provided with a flat upper face forming a support for the overlapping slotted extremities 28 of the two rods.

Located directly above the reinforcement 30 is a cylinder 31, which is rotatably mounted in an opening formed in the top of the part 27, the latter being equipped with a collar 32 upon which a top flange 33 formed on the cylinder rests. The two flattened and slotted overlapping rod extremities occupy a position between the cylinder 31 and the reinforcement 30. The cylinder is equipped with an opening for a key 34, while directly below the key opening is a space 35, between the overlapping extremities of the two rods, when the latter are at their outward limit of movement under the influence of their springs 19. Hence it becomes practicable, when the rods are in the locking position (see Figs. 2 and 3), to insert the key in the cylinder and cause its inner extremity to pass between the outer extremities of the overlapping rods. Then, by turning the key from the full line to the dotted line position (see Fig. 2), or giving it a quarter turn, the two rods may be ac-

tuated to draw their outer extremities inwardly sufficiently to disengage their bevelled ends from the teeth 14 of the ratchet arms 12. When this is done, the bar 18 will be released and may be lifted or entirely disengaged from the arms 12 of the robe rail, thus permitting the removal of robes or other articles from, or placing them upon, the robe rail, as may be desired.

From the foregoing description, the use of my improved device will be readily understood. Assuming that it is desired to place robes or other articles upon the robe rail, the bar 18 may, if desired, be removed from the arms 12, allowing the desired articles to be hung freely upon the robe rail. The bar 18 is then placed in position with its extremities straddling the upright arms 12 of the rail. In this event, the outer extremities 15 of the rods 17 will enter the grooves 13, and, as the bar is forced downwardly, the ends of the rods will slip past the teeth of the arms until the bar is lowered sufficiently to secure the articles upon the robe rail in clamping relation against possible removal. When the bar 18 is in this position, the outer extremities of the rods interlock with the teeth of the arms 12 and can only be disengaged therefrom by the use of the key 34, as heretofore explained. The cylinder 31 may, if desired, carry tumblers, and, as heretofore intimated, may be made as complicated or as difficult to be tampered with, as desired.

Having thus described my invention, what I claim is:—

1. The combination with a robe rail, of upwardly-projecting arms equipped with ratchet teeth, a bar having its extremities constructed to straddle the said arms, the bar having a hollow upper portion, two rods located in the upper portion of the bar and arranged to overlap, the said rods being spring-actuated to cause their outer extremities to protrude beyond the ends of the bar, the said protruding extremities of the rods being arranged to interlock with the teeth of the said arms, and suitable means for actuating the said rods to disconnect their extremities from the teeth of the arms, substantially as described.

2. The combination with a robe rail, of upwardly projecting arms, a bar having its extremities constructed to straddle the said arms, a ratchet and pawl connection between the bar and the arms, the bar being formed concavo-convex with its concave surface lowermost, the lower part of the bar having inturned flanges flexibly arranged to co-operate with the robe-rail for robe-securing purposes, substantially as described.

3. The combination with a robe rail, of upwardly projecting arms equipped with ratchet teeth, a bar having its extremities constructed to straddle the said arms, and

having a longitudinally disposed cavity in its upper surface, spring-actuated rods located in the said cavity, their outer extremities being arranged to engage the ratchet teeth of the said robe rail arms, the inner extremities of the rods overlapping each other and provided with openings adapted to receive a key for withdrawing the rod extremities from the ratchet teeth of the arms, the upper part of the bar having a cylinder centrally located to receive the said key, the lower part of the bar being interposed between the robe rail arms and constructed to coöperate with the robe rail for garment securing purposes, substantially as described.

4. The combination of a robe rail equipped with upwardly projecting arms having vertically disposed grooves provided with ratchet teeth, the robe rail also having bracket arms for fastening purposes, and a bar arranged to straddle the said arms and carrying in its upper portion spring actuated rods whose extremities extend beyond the extremities of the bar and coöperate with the ratchet teeth of the arms, the inner extremities of the rod overlapping each other and being adapted to receive a key for un-

locking purposes, the central portion of the bar having a rotary cylinder adapted to receive the key, the lower part of the bar being interposed between the said arms and coöoperating with the body of the robe rail for garment securing purposes, substantially as described.

5. The combination of a robe rail having upwardly projecting arms, and a bar vertically movable between the said arms, an interlocking connection between the extremities of the bar and the said arms, the central portion of the bar being constructed to receive a key, an operative connection between the key and the interlocking parts, the lower portion of the bar having its lower surface concave, and its lower edges bent upwardly into the said cavity, the upwardly projecting parts being adapted to yield as the bar is forced downwardly into clamping relation with the articles interposed between the bar and the robe rail, substantially as described.

In testimony whereof I affix my signature in presence of two witnesses.

VERKIE LUCAS DE DONTNEY.
